UNITED STATES PATENT OFFICE.

RAPHAEL ESTURO, OF NEW YORK, N. Y.

UMBRELLA.

1,353,034.

Specification of Letters Patent. Patented Sept. 14, 1920.

Application filed September 18, 1919. Serial No. 324,457.

To all whom it may concern:

Be it known that I, RAPHAEL ESTURO, a citizen of the United States, and a resident of the city of New York, borough of Manhattan, in the county and State of New York, have invented a new and Improved Umbrella, of which the following is a full, clear, and exact description.

The present invention relates to new and useful improvements in umbrellas, and it pertains more particularly to the handle structure thereof.

The primary object of the invention is to provide an umbrella in which the top is capable of rotary movement relative to the handle.

A further object of the invention is to provide an umbrella in which the handle may be removed.

With the above and other objects in view, reference is had to the accompanying drawings, in which—

Figure 1 is a detail sectional view of one form of the invention;

Fig. 2 is a similar view of a modified form of the invention;

Fig. 3 is a transverse sectional view taken on the line 3—3 of Fig. 1;

Fig. 4 is a transverse sectional plan view taken on the line 4—4 of Fig. 2.

Referring more particularly to the drawings, the reference character 5 designates an umbrella handle, and said handle is provided with a socket 6, in which is suitably secured a tubular member 7. The tubular member 7 projects beyond the handle, and said projecting portion is provided with two annular flanges 8 and 9, spaced with respect to each other, to form a channel 10.

The reference character 11 designates the umbrella staff, and secured to one end thereof is a tubular member 12. This tubular member 12 is provided with a closed curved end 13, which is adapted to engage the bottom wall of the tubular member 7, the curved end being provided to reduce the friction to a minimum.

The outer end of the tubular member 12 is provided about its diameter, at equidistantly spaced points, with lugs or ears 14, and said lugs or ears 14 are adapted to be bent around the outer flange 9 into the space between the flanges 8 and 9, as indicated by the reference character 15 in Fig. 1.

By this construction it will be seen that the staff 11 and its tubular member 12 are

freely rotatable with respect to the handle 5, the tubular member 12 rotating within the tubular member 6, and the lugs 14 serving to hold the several parts in the positions shown.

In the form of the invention illustrated in Fig. 2, the reference character 20 designates a tubular member, which is placed within a socket 21, in the handle 22. This tubular member 20 is provided exteriorly with oppositely-disposed resilient members 23, the outer end of each of which is provided with a curved seat 24. The reference character 25 designates a tubular member, which is rigidly secured to the staff 26, and the inner closed end of this tubular member 25 is curved as indicated by the reference character 27.

Surrounding the staff 26 in such a manner that it engages the free outer end of the tubular member 25, is a coil wire 28, the outer face of which engages the curved seat 24 of the resilient members 23, as indicated in Fig. 2. By this construction, it will be apparent that so long as the wire is engaged with the staff 26, by reason of the engagement of the outer end of the tubular member 25 with the coil of said wire, the withdrawal of the staff 26 is prevented.

For the purpose of removing the staff, the free ends of the wire 28 are crossed, as indicated by the reference character 30, and each end is provided with an operating knob 31. From this it will be seen that as the knobs are forced together, the coil 28 is expanded to such a position as to permit of the free passage of the tubular member 25 in order that the staff with said tubular member 25, may be withdrawn from the handle socket.

From the foregoing description, it will be seen that in both forms of the invention, the staff in addition to being removable, is free to rotate in the handle, thus relieving the umbrella of shocks owing to contact with various obstacles when in the raised position.

I claim:

1. In an umbrella, a handle provided with a socket, a staff adapted to be received within said socket and rotatably mounted with respect thereto, and resilient means carried by said socket and embracing said staff for retaining the staff within the socket.

2. In an umbrella, a handle provided with a socket, a staff, a sleeve member carried by

the staff and adapted to be received within the socket, and resilient means carried by the socket and adapted to engage the free edge of the sleeve carried by the staff to prevent displacement of the staff within the socket.

3. In an umbrella, a handle provided with

a socket, a staff, a sleeve member carried by said staff and immovably secured thereto, and a resilient member carried by the socket and engaging the staff and the free edge of the sleeve carried thereby to retain said staff within the socket.

RAPHAEL ESTURO.
